CLAIM

The ornamental design for a toilet roll holder, as shown and described.

DESCRIPTION

FIG. 1 is a right side elevational view of a toilet roll holder showing my new design, the right side being a mirror image and the broken-line depiction of a portion of the wall being for illustrative purposes only and forming no part of the claimed design;
FIG. 2 is a top plan view thereof;
FIG. 3 is a front elevational view thereof;
FIG. 4 is a rear elevational view thereof;
FIG. 5 is a bottom plan view thereof; and
FIG. 6 is a vertical cross-sectional view thereof, taken along line VI—VI of FIG. 3.
